NORMAN BURDICK, OF ALBANY, NEW YORK, ASSIGNOR TO HIMSELF, JACOB H. SHEAR, AND JOSEPH PACKARD, OF SAME PLACE.

Letters Patent No. 78,924, dated June 16, 1868.

IMPROVEMENT IN CUPOLA-FURNACES.

The Schedule referred to in these Letters Patent and making part of the same.

TO ALL WHOM IT MAY CONCERN:

Be it known that I, NORMAN BURDICK, of the city and county of Albany, and State of New York, have invented a new and useful Improvement in Cupolas for Melting-Furnaces; and that the following is a full and exact description thereof, reference being had to the accompanying drawings, and to the letters marked thereon, and making a part of this specification.

My said improvement consists in an improved bottom to said cupola, and in its peculiar construction and arrangement, with reference to the discharging and confining the products or refuse coal, cinders, &c., left in the bottom of the cupola, after the melted iron has been drawn therefrom, so as to compel the smoke, heated air, and noxious gases to escape through the cupola into the outer air, instead of escaping into the building, to the great annoyance and hindrance of workmen; and my said improvement has reference, also, to the protection and preservation of the bottom of the cupola from the injurious and destructive effects of allowing the heated mass or residuum of a blast to remain in contact with the bottom, after discharging the same into the pit beneath.

In the accompanying drawing—

Figure 1 represents a vertical section of a cupola, with my improvement attached, in which B' B' represent the outer shell of the cupola; S S represent the lining fire-brick; F F, the base of the shell B' B'.

B B represent the sections of my improved bottom, and A A represent an inlaid sheet of fire-clay, fire-brick, or any other non-fusible substance, for the protection of the bottom, B B, from the effect of melted iron, which sometimes finds its way through the sand in the bottom of the chamber of the cupola, upon the iron bottom. a a a a represent the truck-wheels, attached to the bottom, B B, by which the same is made to move backward and forward upon the rail or guide R R. b b represent a cam-lever, by means of which the bottom, B B, is made to fit tight to the bottom of the shell and fire-brick of the cupola. P P is the pit, into which the refuse or residuum of the blast is discharged, by withdrawing the bottom, B B. E E represent the axle or wheels, by means of which, and a chain connecting each with said axle or wheels, the section of the bottom is withdrawn, and the chamber of the cupola is emptied of its contents.

Figure 2, in the accompanying drawing, represents a vertical view of the improved bottom and its arrangements, presenting a horizontal section of the cupola at or near its base. In this figure one section of the bottom, B B, is represented as withdrawn; the other section is represented in its place, partially concealed by the base of the shell F F. C in this figure represents a stationary covering of one end of the pit, against which the section, B, is situated when withdrawn. The axle around which the chain is wound, in withdrawing the bottom, is seen at D.

Figure 3 represents the windlass or wheel E E.

Figure 4 represents the stationary covering C, which is omitted to be represented at the left hand of figs. 1 and 2 in the drawing.

The advantages of my improvement in the bottom of cupola-furnaces are many.

In the ordinary furnace, the bottom of the furnace is attached to the shell by means of hinges, and is held in position, to sustain the contents of the cupola, by means of a shore or prop standing underneath the same, and the chamber is emptied of the residuum of the blast by removing the prop, and allowing the bottom to swing down, falling into the midst of the melted cinders or residuum, by reason of which it becomes heated, burned, and warped, soon destroying it, or rendering it unfit for use, and rendering repair or renewal necessary, with great delay, expense, and damage.

Beside, this method of discharging the contents of the cupola into the pit causes the heated air, gases, and smoke to fill the building in which the cupola is situated, and renders it difficult or impossible to remove the heated cinders, &c., or to close again the bottom of the chamber of the cupola, until by radiation the cinders are cooled off, occupying many hours.

By means of my improvement all these difficulties are obviated.

Instead of dropping down the bottom of the cupola among the heated cinders, I withdraw it to one side, and it serves as a cover to the pit, preventing the smoke, gases, &c., from escaping into the building, and the chamber of the cupola thereby becomes a chimney to the pit, through which the smoke, gases, &c., escape into the outer air.

In the ordinary cupola-furnace, the bottom, B, is made of iron only, and the melted contents of the cupola sometimes work down through the sand in the bottom of the chamber, and melt out or cut away the bottom of the cupola. I obviate this difficulty by inlaying so much of the bottom as may be thus exposed to danger, with some non-fusible substance, as fire-clay or its equivalent. This is represented in fig. 1 by A A.

The operation of my improvement is as follows: When I wish to charge the cupola, the bottom sections are brought into place, and by means of the cam-levers b b, they are pressed firmly against the bottom shell of the cupola, bringing the cam-levers into a perpendicular position, to act as props to keep the bottom in place. When it is desirable to discharge the cupola from cinders, &c., the cam-levers are drawn aside to let the bottom, B, fall away, as shown in the left section of fig. 1, in the drawing attached, thus rendering it easy to withdraw the section by means of the wheel, axle, and chain, as above set forth.

This being done, the sections of the bottom are withdrawn, and the contents of the cupola fall into the covered pit P P, and the chamber of the cupola becomes the chimney of the pit.

The pit is constructed in the form of a section of an inverted pyramid, to prevent the compacting of the cinders, &c., therein. There may be other outlets to this pit, through which the smoke, gases, &c., may be conducted away, while the bottom of the chamber of the cupola is closed for the purpose of recharging the cupola.

Having thus fully described the nature of my said improvement, I will proceed to set forth my claims.

1. I claim the use of a sliding bottom to a cupola-furnace, constructed substantially in the manner and for the purpose above described.

2. I claim the inlaying of such bottom with some non-fusible substance, substantially in the manner and for the purpose above described, in combination with the chamber of a cupola-furnace.

3. I claim the cam-levers b b, in combination with the bottom, B B, substantially in the manner and for the purpose above described.

4. I claim the form of the pit, in combination with a cupola-furnace, constructed substantially in the manner and for the purpose above described.

5. I claim the bottom, B B, the wheel and axle D and E, the chain y y, the truck-wheels a a a, the cam-lever b b, the guides R R, in combination with the cupola of a melting-furnace, substantially in the manner and for the purpose above described.

NORMAN BURDICK.
